UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

TRAIN-CONTROL SYSTEM.

1,259,567.

Specification of Letters Patent. Patented Mar. 19, 1918.

Application filed November 30, 1915. Serial No. 64,230.

To all whom it may concern:

Be it known that I, WALTER V. TURNER, a citizen of the United States, residing at Wilkinsburg, in the county of Allegheny and State of Pennsylvania, have invented new and useful Improvements in Train-Control Systems, of which the following is a specification.

This invention relates to automatic train control systems, and more particularly to a system for regulating the speed of the train.

One object of my invention is to provide a train control system in which the speed limit of the train may be increased step by step from a distant point.

Another object of my invention is to provide a train control system in which the speed limit of the train may be increased or reduced from a distant point.

Other objects and advantages will appear in the following more detailed description of the invention.

In the accompanying drawings; Figure 1 is a diagrammatic view of a train speed control system embodying my improvements; Fig. 2 a central sectional view of the speed governor valve device; Fig. 3 a central sectional view of one of the governor controlling valve devices; Fig. 4 a central sectional view of one of the magnet valve devices; and Fig. 5 a fragmentary view showing the construction of the actuating pawl which operates the cam device for adjusting the tension of the governor spring.

According to my invention, insulated contact sections 1 and 2 are arranged at desired intervals between the track rails 3, the sections 1 being connected to a common line wire 4, leading to a distant point where the circuits are controlled and the contact sections 2 to a wire 5 leading to the same point. At the distant point there is provided a source of current 6 having a ground connection at 7 and suitable switches 8 and 9 for respectively controlling the connection of the source of current with the line wires 4 and 5.

Preferably on each car of the train there is provided a speed controlled governor 10, valve devices 11 and 12 connected by pipes 13 and 14 to the speed governor 10 for effecting the adjustment of same, magnet valve devices 15 and 16 connected by pipes 17 and 18 to the valve devices 11 and 12 for effect-

ing the operation of said valve devices, relays 19 and 20 for controlling switches 21 and 22 which in turn control local circuits of the magnet valves 15 and 16 containing the respective sources of current 23 and 24.

The relays 19 and 20 are connected to respective wires 25 and 26 leading to brushes or contact members 27 and 28 adapted to engage the respective contact sections 1 and 2 as the train passes over the track.

Fluid under pressure for operating the valve devices 11 and 12 is supplied from a reservoir 29 connected by pipe 30 to said valve devices.

As shown in Fig. 2 of the drawings, the speed governor 10 may comprise a casing in which are mounted speed governor balls 31, the centrifugal force of which is adapted to effect the movement of a spindle 32. The tendency of the balls 31 to fly out as the speed increases is opposed by springs 33 and 34 which act through a plate 35 against one or more pins 36. A disk 37 carries the pins 36 and spring pressure is transmitted from said disk, preferably through a ball bearing 38, to a disk 39 secured to the spindle 32. Movement of the spindle 32 by the centrifugal action of the governor balls is adapted through the disk 37 to open a valve 40 for venting fluid from a pipe 41 leading to a valve device (not shown) adapted to effect an application of the brakes.

In order to vary the speed limit at which the governor acts, means are provided by adjusting the spring pressure step by step comprising a cam plate 42 adapted to engage a roller 43 carried by a stem 44. A spring plate 45 engaging the lower ends of the springs 33 and 34 is secured to the stem 44 and when the cam 42 is rotated, the stem 44 actuates the spring plate 45 to compress the springs.

For rotating the cam plate 42, a ratchet wheel 46 is secured to the cam shaft 47 and a pawl 48 is provided for engaging the teeth of the ratchet wheel.

The pawl 48 is pivotally mounted on the end of a piston stem 49 provided with a piston 50 contained in a piston cylinder 51 and a spring 52 is mounted in a cavity in the pawl so as to engage a projection on the stem 49. When the piston 50 is in normal position, as shown in Fig. 2 of the drawings, the inner end of the pawl engages the

end face of the cylinder 51 and maintains said pawl out of engagement with the ratchet wheel 46. Upon outward movement of the pawl, the spring 52 acts to throw the 5 pawl into working engagement with the ratchet wheel.

For rotating the cam plate 42 in the opposite direction, a pinion 53 is secured to the cam shaft 47 and a rack 54 on the piston 10 stem 55 of a piston 56 is adapted to engage the pinion, the piston being contained in a piston cylinder 57. The valve devices for controlling the fluid pressure on the pistons 56 and 50 may be of the same construction 15 and as shown in Fig. 3 may each comprise a piston 58 mounted in a piston chamber 59 for operating a slide valve 60 contained in valve chamber 61.

Each of the magnet valve devices 15 and 20 16 may be connected as shown in Fig. 4 of the drawings, there being provided a magnet coil 62 for controlling a valve 63.

In operation, the switches 21 and 22 are 25 normally open and the magnet valve devices 15 and 16 are held deenergized. Fluid under pressure is supplied from the reservoir 29 through pipe 30 to the valve chamber 61 of each valve device 11 and 12. Thence fluid equalizes through a small port 64 in 30 piston 58 to piston chamber 59 and the piston is maintained in normal position by a spring 65. In this position, pipe 13 is connected by passage 66 and cavity 67 with an atmospheric exhaust port 68, so that there 35 is now atmospheric pressure in the piston cylinder 57. Similarly, the piston chamber 51 is connected to the atmosphere by the valve device 12.

With the centrifugal governor in its lowest 40 position, as shown in Fig. 2 of the drawings, the adjustment is such as to cause the governor balls to open out at a certain predetermined low speed, say 10 miles per hour. If, therefore, the speed of the train 45 exceeds this limit, the movement of the governor balls will operate the plate 37 against the resistance of the spring 33 and cause the valve 40 to be opened. Fluid is thereupon vented from pipe 41 to exhaust 50 port 69 and an application of the brakes is effected by operation of the brake application valve. When the speed of the train falls below the speed limit for which the governor is adjusted, the governor balls 55 drop down and permit the valve 40 to close and the brakes are then released. It will thus be seen that so long as the governor adjustment remains the same, the speed of the train cannot exceed the predetermined speed 60 limit for which the governor is adjusted.

If it is desired to permit an increase in the speed limit of the train, the switch 9 is closed at a distant point or by operation of a signal system. All of the contact sections 65 2 in the local block are then connected to the

grounded source of current 6 and when the train passes over one of these sections, a circuit will be closed through the relay 20, so as to effect the closure of switch 22. The magnet valve device 16 is thus energized by 70 current from the source 24 and valve 63 is opened to vent fluid from piston chamber 59 through pipe 17 to exhaust port 70. The sudden reduction in pressure in piston chamber 59 causes the outward movement of 75 piston 58, so as to connect passage 71 through cavity 67 with passage 66. Fluid is thereupon supplied from reservoir 29 to the piston 50 which is moved outwardly, causing the pawl 48 to engage the ratchet 80 wheel 46 and turn same the space of one tooth. The cam plate is thus rotated, so as to elevate the roller 43 and thereby effect the movement of the spring plate 45 to compress the spring 33 a certain amount. The 85 spring tension on the governor being increased, it will require a greater train speed to cause the governor balls to fly out and open the valve 40. For example, the adjustment may be such as to require a train speed 90 of 15 miles per hour to open the valve.

The train speed will now be controlled as in the first instance and when the speed exceeds the increased speed limit the brakes 95 will be applied and the train speed reduced.

When the train passes off an energized contact section 2, the relay 20 will be deenergized, and the switch 22 again opened. The valve 63 thereupon closes and equalization of fluid pressures on the piston 58 is 100 effected through the port 64. The piston 58 is returned to normal position by the spring 65 and the fluid pressure on piston 50 is vented to the exhaust port 68. Spring 72 will then shift the piston 50 and pawl 48 105 back to normal position, but the cam plate 42 will remain in its adjusted position.

If the speed limit of the train is to be maintained at 15 miles per hour, the switch 9 is opened, so that there will be no energization of the relay 20 as the train passes over succeeding contact sections 2. If, on the other hand, it is desired to increase the speed limit another step of say 5 miles per hour, the switch 9 is closed, so as to effect 115 the energization of the relay 20 as the train passes over succeeding contact section 2.

In the same manner as previously described, the piston 50 will then be actuated so as to cause the pawl 48 to rotate the 120 ratchet wheel 46 another tooth. The tension of spring 33 is thus increased and a correspondingly increased train speed is necessary to effect the outward movement of the governor balls.

The speed limit of the train may thus be increased step by step as the train passes over successive contact sections 2.

When the spring plate 45 has moved a certain distance, the spring 34 is caused to 130

act, so that the combined resistances of both springs 33 and 34 is effective during the further movement of the cam plate.

If it becomes necessary to reduce the speed of the train, the switch 8 is closed and the contact sections 1 in the local block are connected to the source of current 6. When the train passes over the next contact section 1, the relay 19 is energized so as to close switch 21 and cause the magnet valve 15 to be energized.

The valve device 11 is thereupon operated so as to supply fluid under pressure to piston 56. It will be noted here that the piston 56 is moved by the rack 54 and pinion 53 when the cam plate 42 is rotated, so that said piston may be in some intermediate position in the piston cylinder 57 according to the position of adjustment of the cam plate 42.

Whatever the position of piston 56, however, fluid admitted thereto will shift same to its extreme outer position, so that the cam plate will be returned to its lowest position, as shown in Fig. 2. The governor is thus adjusted to the minimum speed limit and if the train speed exceeds this speed limit, an application of the brakes is made and continues until the speed of the train has been reduced to or slightly less than the minimum speed allowed.

The speed of the train may be maintained at the minimum if the switch 8 is left open, or the speed limit may again be raised by closing the switch 9. Each vehicle of the train is preferably equipped with the speed control apparatus, so that in case of possible failure of the apparatus on one car to act, that on another car will be effective.

Having now described my invention, what I claim as new and desire to secure by Letters Patent, is:

1. In a train speed control system, the combination with apparatus for limiting the speed of the train, of means controlled from a distant point for increasing the train speed limit step by step.

2. In a train-speed control system, the combination with a speed governor operated according to the speed of the train for effecting an application of the brakes, of means controlled from a distant point for effecting a step by step adjustment of the governor and a corresponding step by step increase in the speed limit at which the governor acts to effect an application of the brakes.

3. In a train speed control system, the combination with apparatus adapted to effect an application of the brakes upon the speed of the train exceeding the speed limit at which said apparatus is adjusted to operate, of means controlled from a distant point for adjusting said apparatus to increase the operating speed limit thereof step by step.

4. In a train speed control system, the combination with a speed governor adapted to be operated according to the speed of the train for effecting an application of the brakes, of means controlled from a distant point for progressively adjusting said governor at predetermined intervals along the track to effect corresponding progressive increases in the operating speed limit of the governor.

5. In a train speed control system, the combination with a speed governor operated according to the speed of the train for effecting an application of the brakes and resilient means for opposing the effect of the train speed on the governor, of a cam device for increasing the resistance of said resilient means and a pawl and ratchet adapted to be controlled from a distant point for operating said cam device.

6. In a train speed control system, the combination with a speed governor operated according to the speed of the train for effecting an application of the brakes and a spring for opposing the effect of train speed on the governor, of a cam device operatively connected to said spring and adapted upon rotation to compress the spring, a ratchet wheel connected to said cam device, and a pawl operated from a distant point for rotating the ratchet wheel.

7. In a train speed control system, the combination with a speed governor operated according to the speed of the train for effecting an application of the brakes, of means controlled from a distant point for adjusting said governor to operate at an increased train speed limit and means controlled from a distant point for adjusting said governor to operate at a reduced train speed limit.

8. In a train speed control system, the combination with a speed governor operated according to the speed of the train for effecting an application of the brakes, of means controlled from a distant point for adjusting said governor to progressively increase the train speed limit at which the governor operates and means controlled from a distant point for adjusting said governor to reduce the speed limit at which the governor operates to a minimum.

9. In a train speed control system, the combination with a speed governor operated according to the speed of the train for effecting an application of the brakes, of means controlled from a distant point for adjusting said governor to increase at one time and at another time reduce the train speed limit at which the governor operates.

10. In a train speed control system, the combination with a speed governor adapted to effect an application of the brakes at a predetermined train speed, of mechanism for adjusting the governor to act at differ-

ent train speed limits, a fluid operated piston for actuating said mechanism, a valve device for varying the fluid pressure on said piston, a magnet controlled valve for effecting the operation of said valve device, a relay and a switch operated thereby for controlling the circuit of the magnet, contact sections along the track adapted to be engaged by a contact in the relay circuit on the vehicle, and a switch located at a distant point for controlling the electrical condition of the contact sections.

11. In a train speed control system, the combination with means governed by the

speed of the train for regulating the train speed, of mechanism for adjusting said means to operate at an increased train speed, mechanism for adjusting said means to operate at a reduced train speed, a series of electric contact sections located along the track for electrically controlling each mechanism, and switch devices located at a distant point for controlling the electrical condition of each series of contact sections. 15 20

In testimony whereof I have hereunto set 25
my hand.

WALTER V. TURNER.
